UNITED STATES PATENT OFFICE.

JOHN M. SCOTT, OF RACINE, WISCONSIN, ASSIGNOR TO OTTO R. BARNETT, OF CHICAGO, ILLINOIS.

RAIL-ANCHOR.

1,090,946.

Specification of Letters Patent. Patented Mar. 24, 1914.

Application filed August 26, 1913. Serial No. 786,647.

To all whom it may concern:

Be it known that I, JOHN M. SCOTT, a citizen of the United States, residing at Racine, in the county of Racine and State of Wisconsin, have invented certain new and useful Improvements in Rail-Anchors, of which the following is a specification.

My invention relates to devices for preventing the longitudinal creep of railroad rails, these devices being commonly known as rail anchors, rail stays or anti-creepers.

The object of the invention is to provide a device of this sort which will be very strong and reliable in its hold upon the rail which cannot be easily loosened or shaken off the rail by the vibration of the latter, or similarly disturbing influences, and which, furthermore, will be very simple in its construction, easily put in place by unskilled labor, and which will also be very inexpensive to manufacture.

A more particular object of the invention is to provide an improved one-piece rail anchor of the type which is provided with an abutment and jaw at one end and a jaw at the other end, arranged in such relation to each other that the jaw at the end opposite the abutment is held away from the tie so that, while the device is applicable to the base of the rail by applying it in an angular position and then turning it to gripping position, in which position the tendency of the rail to creep also tends to further twist the device and tighten its grip upon the rail.

With such devices, however, there is a tendency to come loose from the rail whenever the contraction of the rail carries the device with it and so draws the abutment away from the tie. Under those conditions, va-

rious causes, such as the vibration caused by a passing train, tend to shake the device loose unless means are provided to prevent this loosening action. There is also a tendency, even when the device is not shaken loose, to cause it to move backwardly on the rail so that the subsequent expansion of the rail does not bring the abutment in contact with the tie, and hence the abutment, which furnishes the fulcrum for the canting action of the device, becomes inoperative, and there is no tension to hold the device in gripping engagement with the rail.

It is the purpose of my invention to so construct a device of this character that, after it has been applied to the rail, a part

thereof may be bent to bring the device into such tight engagement with the rail that it cannot be shaken loose therefrom and, if properly applied, will at all times hold the rail with a sufficiently tight grip to maintain its original position on the rail, so that, although the abutment may be withdrawn from engagement with the tie by the contraction of the rail, the subsequent expansion of the rail, or any creeping of the rail, will reliably bring the abutment back again into engagement with the tie, whereupon any further tendency of the rail to creep will cause the device to move about the fulcrum furnished by the abutment to insure a rigid and effective anti-creeping grip of the device on the rail.

The one-piece anchor commonly in use at the present time is not altogether reliable in its action for the reason that its method of application to the rail necessitates relatively small areas of effective contact between the gripping portions of the device and the rail, and furthermore, a degree of accuracy in the design and proportioning of the parts of the device which cannot be counted upon in malleable castings turned out in large numbers. Furthermore, these anchors, even when structurally perfect and exactly proportioned to the rails on which they are used, require a certain amount of skill in their application to said rails, or else they fail to operate successfully under practical conditions; one difficulty, for example, being that the jaws must be tightened on the rail and at the same time the abutting portion of the anchor brought into contact with the tie against which the device operates.

My invention provides a rail anchor which while not costing more than the familiar one-piece anchor now used, is much more easily applied to the rail and can be applied so as to take a much firmer and more reliable hold upon the rail.

The broad idea of constructing a rail anchor so that it may be bent, after application to the rail, so as to bring the rail gripping jaws into operative engagement with the rail, is disclosed and claimed in my co-pending application Serial No. 786,646, filed August 26, 1913. Whatever is common to that application and this it is my intention to claim in that application and not in the present one.

The invention is shown, in a preferred em-

bodiment, it being understood that modifications might be made without departure from the principle of the invention, in the accompanying drawings wherein—

- 5 Figure 1 is a side view of the device fitted to a rail, the rail being shown in cross section; Fig. 2, a plan view showing the first position which the device takes in its application to the rail; Fig. 3, a similar view 10 showing the second position, both jaws in this case being in substantially the position which they occupy operatively; Fig. 4, a similar view with the strut or tie abutting member bent and bearing against the cross tie against which the device is pressed when 15 performing its anti-creeper function, and Fig. 5 is a sectional view taken on line 5—5 of Fig. 4.

Like characters of reference designate 20 like parts in the several figures of the drawings.

Referring to the drawings, A designates a railway rail provided with the usual base flanges *a*, and B one of the cross ties on 25 which the rail is supported.

The device of my invention, in the preferred form shown, consists of a single malleable casting formed so as to provide a rail gripping member C, formed at opposite ends 30 with jaws D and E, and a strut F formed with a tie abutting flange G designed to bear against the tie B. Preferably the strut F is composed of two relatively thin webs *f*, *f'*.

The several positions of the device, with 35 relation to the rail shown in Figs. 2, 3 and 4, represent the method of application to the rail. The device is thrust under the rail and one of the jaws D or E, the jaw D for example, fitted over the edge of one of the 40 base flanges A as shown in Fig. 2. The device is designed so that in this case the inner edge of the other jaw E clears the edge of the opposite base flange. The device is then turned to the position shown in Fig. 3. This 45 brings both jaws in engagement with the base flanges of the rail and this engagement, if need be, may be tightened by hammering the device on the rail. The tie abutting flange G of the strut F bears against the tie 50 B. In this position the device is operative on the familiar principle of the typical one-piece rail anchor, as the jaws D and E may be caused to grip the rail with such a sufficiently tight grip that any creeping of the 55 rail toward the tie will rock the device about the abutment as a fulcrum, causing it to more tightly grip the rail. Consequently, my improved device, even if improperly applied, is quite as efficient as the familiar type 60 of one-piece device upon which it is an improvement. In properly applying my device, however, the strut F is now bent and driven to the position shown in Fig. 4 by hammering on its outer end. In the preferred 65 embodiment of my device this brings

the jaw H into such engagement with the rail base that the device cannot be rotated in reverse direction to detach it from the rail. It will be seen that the primary purpose of this jaw H is to so engage the rail when the strut has been bent as to prevent the reverse rotation of the device on the rail, and, therefore, it performs this function regardless of whether it extends over and grips the rail base, or whether it merely abuts against it. 70 Therefore, while the member H is shown and described as a jaw, it will be seen that in purpose and function it is primarily an abutment which may or may not be of a jaw or gripping form. Therefore, in the specification and claims, the term "jaw" as applied to the member H should be understood merely as a term of convenience, applicable to any element performing the primary function of abutting or engaging the rail when the strut has been bent so as to prevent the reverse rotation of the device. Preferably, the jaw E is held snugly in engagement with the rail by means of a crow-bar or any other convenient implement, while the strut 75 is being bent until the jaw H is in gripping engagement with the tapered rail base, thereby bringing the whole device into such snug engagement with the rail that it will not be moved from its position on the rail by vibration or any other usual loosening influences, while the jaw E will have such snug engagement with the rail at all times that any creeping of the rail, when the abutting flange is in engagement with the tie, 80 will inevitably swing the device on the abutment, thus tightening the grip of the jaws D and E on the rail and effectively resisting the tendency of the rail to creep. 85

It will be seen that the broad idea embodied in my improved device is the provision, in a device of this character, of a jaw-carrying member bendable in such manner that the jaw carried thereby shall be brought into a permanent position on the rail, from 90 which position it cannot be removed without bending the jaw-carrying member in a reverse direction. 95

The web *f'* has originally a curved configuration. The web *f* is straighter and is 100 preferably made thinnest at the end nearest the body of the anchor. As a result of this construction the webs will be bent as shown in Fig. 4, that is, web *f* will bend at a point near 105 its junction with the body of the anchor and the web *f'* will bend with more or less uniformity throughout its length. Preferably the web *f'* is formed with a lug *f*² which comes into contact with the web *f* when the strut is bent. By these arrangements the 110 strut, when bent and bearing against the tie, has great strength and capacity for resisting the pressures brought to bear against it. Preferably, though not essentially, the strut is provided with a jaw H which, by 115

engaging the edge of the base flange, assists in holding the device in operative position.

While I have referred, in the description and claims, to the device as bearing against a cross tie, it will be readily understood that the device would operate equally well against any stationary element of the roadbed. The invention is not to be understood as limited to a rail which is laid upon cross ties.

10 I claim:

1. A rail anchor comprising a cross-bar provided at opposite ends with jaws adapted to engage the opposite sides of the base flange of a railroad rail, and a strut provided with an abutment and carrying a

15 third jaw, said strut being bendable so as to bring the third jaw into operative engagement with a rail to which the device has been applied.

20 2. A rail anchor consisting of a single integral casting formed at opposite ends with rail gripping members and provided with a strut carrying an abutment and a rail engaging member, said strut being bendable to bring said rail engaging member into engagement with a rail to which the device has been applied.

25 3. A rail anchor consisting of a single integral casting formed at opposite ends with rail gripping members and provided with a bendable element adapted to bear against a tie on which said rail is supported which consists of two relatively thin webs spaced apart and a tie abutting flange.

30 35 4. A rail anchor consisting of a single integral casting formed at opposite ends with rail gripping members and provided with a bendable element adapted to bear against

a tie on which said rail is supported which consists of two relatively thin webs spaced apart and a tie abutting flange, said element being formed with a jaw adapted to engage the base flange of said rail. 40

5. A rail anchor consisting of a single integral casting provided with two rail engaging members on one side thereof, a rail engaging member on the opposite side thereof, and a strut provided with an abutment and carrying one of said first-named rail engaging members, said strut being arranged 45 to hold the rail engaging member on the opposite side of the rail away from the tie and being bendable to bring the member carried by said strut into engagement with a rail after the device has been applied thereto. 50

6. A rail anchor consisting of a single integral casting formed at opposite ends with rail gripping members and at one end with a strut and tie abutment, a portion of the device being bendable after application to 60 a rail to bring one of the rail engaging members into operative engagement with the rail.

7. A rail anchor consisting of a single integral casting formed at opposite ends with rail gripping members and provided with a bendable element adapted to bear against a tie, said element comprising two relatively thin webs spaced apart, one of said webs being provided with a lug arranged to engage 65 the other of said webs when said member has been bent to final position. 70
